UNITED STATES PATENT OFFICE.

THOMAS C. DE VORE, OF CHICAGO, ILLINOIS.

SMOKING PIPE.

Application filed October 18, 1926. Serial No. 142,177.

My invention relates to smoking pipes and its principal object resides in the provision of a smoking pipe wherein saliva is prevented from accumulating in the bowl and hence obviate the obnoxious objection of the saliva entering the smoker's mouth.

A further object of the invention is to provide a smoking pipe of this character having a removable bowl or tobacco cartridge holder which can be readily removed for the purpose of cleaning the same.

With the preceding and other objects and advantages in mind, the invention consists in the novel combination of elements, constructions and arrangements of parts to be hereinafter specifically referred to, named and illustrated in the accompanying drawing wherein,

Fig. 1 is a side elevation of a smoking pipe constructed in accordance with my invention;

Fig. 2 is a longitudinal vertical sectional view of the same; and,

Fig. 3 is a top plan view with the stem or mouth piece removed.

Referring to the invention in detail wherein the preferred form is illustrated in the accompanying drawing, a bowl fashioned from non-combustible material is designated 30 at 5, the latter having its upper end provided with interior screw threads 6 for threaded engagement with exterior screw threads 7 on a tobacco cartridge holder 8. The sides and bottom of the cartridge holder 8 are 35 spaced from the bowl 5 to provide a smoke chamber 10 which has communication with the cartridge holder by way of outlet openings 9 in the bottom of the latter.

A lateral enlargement 11 is formed on one 40 side of the bowl 5 and extends vertically of the same with its ends stopping short of the upper and lower edges of the bowl. An inverted L-shaped passageway or bore 12 is formed in the lateral enlargement and has 45 one of its branches communicating with the smoke chamber 10 and its other branch leading to the lower end of the enlargement. A threaded nipple 13 is cast with the enlargement 11 and communicates with the vertical 50 branch of the opening 12.

A mouth piece or stem 14 is threaded on the nipple 13. To prevent saliva passing from the smoker's mouth and entering the bowl by way of the stem 14, I provide a

valve mechanism in the passageway 12 to 55 normally close the same but which will be opened by suction or vacuum produced incident to the smoking of the pipe. The valve mechanism in this instance comprises a ball 15 arranged at the point of communication 60 of the two branches of the passageway 12 and normally held against a valve seat 16 at the inner end of the vertical branch of this passageway. An expansible coil spring 17 is positioned in the vertical branch of the 65 passageway and has one end positioned against the ball valve and its other end engaged by an adjusting stem 18 threaded in the lower end of this vertical branch. By adjusting this stem 18 the valve will always 70 be held against its seat to normally sever communication between the bowl and the stem 14. While the type of valve illustrated is a practical one it is obvious other types of valves may be employed and that 75 the present invention contemplates the use of such valves.

From the disclosure it will be apparent that as the smoker draws or sucks upon the stem 14 the valve 15 will be drawn from its 80 seat, permitting smoke to pass from the bowl and smoke chamber through the passageway and thence into the smoker's mouth in the usual manner. As soon as the vacuum or suction is broken the valve is immediately 85 seated, severing communication between the stem 14 and the bowl to prevent saliva from entering the latter.

While I have illustrated and described the preferred form of construction for carrying 90 my invention into effect, this is capable of variation and modification without departing from the spirit of the invention. I, therefore, do not wish to be limited to the precise details of construction set forth, but 95 desire to avail myself of such variations and modifications as come within the scope of the appended claims.

Having described my invention, what I claim as new and desire to secure by Letters 100 Patent is:

1. In a smoking pipe, a bowl, a lateral enlargement formed on said bowl and provided with a passageway communicating with said bowl at a point near the top thereof, a mouth piece communicating with said passageway below the point of communication between said passageway and said bowl, 105

and a check valve arranged in said passageway and operable to open position upon sucking upon the mouth piece.

2. In a smoking pipe, a bowl, a lateral enlargement carried thereby and provided with an L-shaped passageway, a ball valve normally closing one branch of the passageway, an adjusting stem threaded in the lower

end of the vertical branch of the passageway, an expansible spring in the vertical branch of the passageway and engaging the stem and ball valve, and a mouth piece communicating with the passageway.

In testimony whereof I have signed my name to this specification.

THOMAS C. DE VORE.
